CLAIM

The ornamental design for a status indicator light, as shown and described.

DESCRIPTION

FIG. 1 is a front perspective view of the status indicator light showing my new design;

FIG. 2 is a rear perspective view thereof;

FIG. 3 is a rear view thereof;

FIG. 4 is a left side view thereof;

FIG. 5 is a front view thereof;

FIG. 6 is a right side view thereof;

FIG. 7 is a bottom view thereof; and,

FIG. 8 is a top view thereof.

The broken lines shown in the drawings are included for the purpose of illustrating portions of the status indicator light that form no part of the claimed design.
